MESNE ASSIGNMENTS, TO FREDERICK C. STEVENS, OF ATTICA, NEW YORK.

TELEPHONE-EXCHANGE SYSTEM.

1,105,589.

Specification of Letters Patent.

Patented July 28, 1914.

Application filed December 28, 1905. Serial No. 293,630.

To all whom it may concern:

Be it known that I, EDWARD E. CLEMENT, a citizen of the United States, residing at Washington; in the District of Columbia, have invented certain new and useful Improvements in Telephone-Exchange Systems, of which the following is a specification, reference being had therein to the accompanying drawings.

10 My invention relates to telephone exchange systems, and has for its object the provision of means whereby calling subscribers may be answered by operators, the wishes of the calling subscribers communicated in part or in whole by signals, and the desired connections effected by means of automatic mechanism controlled from the subscriber's station.

15 The invention contemplates the use of a smaller number of answering jacks and of a very much smaller number of operators than are now employed in connection with manual switchboards. Certain mechanisms are provided which will be referred to as 20 primary selectors, which are themselves connected to the answering jacks, and which contain terminals of the subscribers' lines. Associated with each answering jack is a 25 pair of indicators, and when a subscriber 30 calls and his line has been picked up by the primary selector of any jack, he sets these indicators to the thousands and hundreds numerals of the number he wants, by manipulating a suitable key or sender at his 35 substation. It should be stated that this sender does no more than to make and break the metallic circuit, there being no grounds outside of the central office. When 40 the operator perceives the indicators set to a number, as for example 24, she plugs into the line-jack to which these indicators belong, and with the other plug of the pair in use she plugs into the trunk-jack of a group numbered 24 and which is connected 45 to an automatic connector switch containing terminals to subscribers' lines numbered from 2400 to 2499. The operator thus does not speak to the subscriber, and as soon as the latter receives an indication which I 50 provide to show he is connected to the automatic switch, he again works his sender, and thereby works the switch, to secure connection with the desired line.

My invention is illustrated in the accompanying drawings, wherein—

55

Figure 1 is a diagram showing a subscriber's station and line-circuit, primary selector switch mechanism with answering terminals and a cord-circuit at the central office. Fig. 2 shows a trunk leading to an automatic connector switch, and a subscriber's line having terminals in the banks thereof. Fig. 3 shows a type of automatic connector switch which may be employed in this system. Fig. 4 is a detail bottom plan view 65 thereof.

60

Referring to the drawings, and particularly to Fig. 1, A is the subscriber's station connected to the central office by line-wires 1 and 2, which terminate in contacts n , n' , 70 of the cut-off relay N, through which they are normally connected, the first to the line-relay M, and the second to ground through wire 3. At the subscriber's station I place the usual apparatus employed in common battery systems, viz., receiver, transmitter, ringer and condenser, with a switch-hook to open and close the metallic circuit through the talking set. I also place thereat two special pieces of apparatus which, however, 75 may be dispensed with where the subscriber is possessed of sufficient skill. The first of these is a key K for sending the numbers wanted and thereby manipulating the mechanism at the central office. The second is a 80 special signal device Q, having a pair of magnets and an armature like those of the ordinary polarized ringer, but with a small target on the end of the clapper rod instead of the clapper. This signal device is connected in series with the talking set, and is low-wound, but may be connected in shunt therewith, and in that case would be very 85 high-wound. Its purpose is to inform the subscriber after he has called, of the fact 90 that his call has received attention, or that his line is connected at the central office, so that he can proceed to signal.

90

When the cut-off relay N is energized, it pulls in the contacts n , n' , and connects the 100 line-wires 1—2 onto the extension wires 5 and 4, terminating in contacts o , o' , of a primary selector switch O. The subscribers' lines have no other answering terminals than the contacts o , o' , and the functions of the primary selector switch which contains the an- 105

swerrings terminals of one hundred lines, is to pick up any one of these when calling, and connect the same onto the jack J , forming the trunk terminal for the switch 5 O . This jack J has spring contacts j , j' , a resting anvil for the former j^2 , and a sleeve contact, j^3 . The purpose of the resting anvil, j^2 , is to permit of cutting off certain circuits in the jack. Obviously, however, 10 this may be accomplished by the use of a cut-off relay and the jack thereby simplified, if desired. The springs of the jack are connected respectively to the wires 10 and 9, leading to what I may term "bus" 15 contacts o^2 and o^3 in the bank of the primary selector O . These bus-contacts are preferably annular combs or rings having inwardly projecting radial teeth, one tooth on each ring corresponding with and lying 20 opposite each contact o or o' . Above each contact o' , and corresponding to its line, is a pair of test contacts o^4 , o^5 , the function of which will presently appear. The operating parts of the primary selector are carried 25 upon and actuated by a spindle o^6 , which I have shown constantly driven through a belt and pulley. On this spindle is carried a hub o^7 having a radial arm o^11 forming the tube for a magnet spool with two windings 30 o^9 , o^{10} . In this tube is fitted to slide the combination core and plug o^{12} , o^{13} , the core portion being of soft iron, and the plug portion being of insulating material, such as hard rubber. The two are secured together 35 in any suitable manner, as by means of a threaded stud on the end of the core tapped into the plug. The plug is normally retracted by a spring within a cap on the outer spool-head of the magnet or solenoid, and 40 this retraction forces the inner end of the core to engage a notch in the spindle o^6 , whereby the tube o^11 and its connected parts are normally carried around by the spindle in its motion. The windings o^9 , o^{10} on the 45 magnet are connected to spring-contact wipers o^{14} , o^{15} which travel over the series of line test contacts o^4 , o^5 . On the other side each winding is grounded. When any line relay M is energized it puts battery through 50 the wire 6 on the wire 7 to contact o^4 , and thence when the spring o^{14} comes around to that contact, through said spring to the magnet winding o^9 and ground. This pulls out the core o^{12} , projecting the plug o^{13} between 55 the springs o^2 , o^3 , and closing them upon the line springs o , o' . The line is then connected by way of wires 4, 5, 10, and 9 to the contact springs j , j' , wire 10 being also connected through the anvil j^2 and wire 11 to 60 main battery B through an inductive resistance M' .

12 indicates the main battery wire or bus, which supplies the various pieces of apparatus. At the same time the wire 9 is connected through wire 13 to a switch-arm m ,

thence by wire 14 to the magnet M^2 and ground. A complete path for the main battery can therefore be traced out through the wires 10, 4 and 2 to the substation and back over the wires 1, 5, 9, 13 and 14 to ground 70 through magnet M^2 , which becomes energized and pulls up its armature, the first effect of which is to connect the battery extension wire 15 with the wire 8 leading to the holding contact o^5 , and thence through 75 the spring o^{15} to the winding o^{10} of the primary selector, and to ground. The winding o^{10} thereafter maintains the core o^{12} in position, the other winding o^9 losing current, as soon as the line-relay M is cut off, which occurs as soon as the condition to which I have referred is established; for a part of the current flowing over wires 10, 4 and 2 is diverted to ground through the cut-off relay N . Moreover, it is imperative that 80 the contact o^4 be rendered dead during continued operation, for the reason that this contact is supposed to be only one of a plurality of multiple-contacts to which the wire 7 is connected. In other words, this wire 7 85 representing the line 1-2, and also the line extensions 5-4, is multiplied into a number of the primary selectors O , so that the first primary selector which happens to be idle 90 will pick up the calling line. Ten of these 95 primary selector switches to one hundred lines at present appears to be about the proper proportion, so each line will have ten multiples. Now, if a contact o^4 were to be left alive for any length of time, with its 100 potential raised, then the potential of all of its multiples would also be raised, and the other switches would get false signals so that more than one of them might stop on the same line. As these multiples are on 105 the line side only, however, they can be cut off after the switch has plugged in on the line calling, provided that another controlling means associated with the switch itself is then rendered active. This comprises the 110 second coil or winding o^{10} , and its circuit through the wiper o^{15} and the ring contact o^5 , connected through wire 8 to the front contact of the relay M^2 , which becomes energized by return current from the line 115 through the wires 9 and 13, the switch-arm m , and the wire 14 to ground, as soon as the line is put on the wires 9-10. This controlling circuit being purely local to the switch, maintains the same in connection 120 with the line until the end of the connection, without risk of interference with other switches.

Associated with each spring jack J is an indicating device I , having a pair of electro-magnets i , i' and a pair of indicating wheels i^4 , i^5 , supported on a pair of shafts or spindles i^2 , i^3 . I do not illustrate the details of this indicator as such devices are well-known in the art of signaling, and in itself, that is 125 130

to say in its construction, it forms no part of my present invention. The number-wheel i^4 is controlled by the electro-magnet i , through a pawl working in a ratchet wheel 5 attached to the indicator; and the number-wheel i^5 similarly controlled by the electro-magnet i' . This indicating device may be controlled by the subscriber to show the thousands and hundreds digits of the line 10 he wants, whereby the operator may at once connect him to a connector switch having terminals of the desired hundred, only one set of these switches being therefore required, and great economy both in the 15 amount of apparatus and in operating expense being effected.

When a subscriber calls, the first thing that happens is the connection of his line to an answering-jack J , as I have already 20 pointed out. By tracing the battery circuits it will be observed that battery being normally connected to the No. 1 side of his line, is thereafter connected to the No. 2 side of line, or the direction of current flow 25 in the line is reversed. The signal Q is thereupon effectively energized, and throws up its target to show the subscriber that he may proceed with the signaling. By the manipulation of the key K , he then sends 30 the first two digits of the whole number wanted, the same being received first on the indicator wheel i^4 , and the second being received by the wheel i^5 . The operator receiving this number set up, at once plugs 35 the subscriber through onto a connector switch-trunk bearing that number, all of the trunk multiples in front of each operator being divided into groups, and marked from 1 to 99. The means by which the indicators 40 are successively brought into circuit, and operated will now be described.

m, m' are two switch-arms connected and moving together, and each having three contact points, on the first of which it normally rests. The magnet M^3 steps these switch-arms around through a pawl and ratchet mechanism, a suitable detent being provided, 45 which is controlled by the magnet M^4 , which acts to release the arms and restore the entire indicator mechanism when the answering plug P is placed in the answering jack J .

When the line 1-2 becomes connected through the wires 9-10 with the jack J , current flows from the battery B through 50 the battery wire 12, magnet M' , and wire 11 to the spring j of the jack and so through the wire 10 out to the line-wire 2 to the substation A , through the talking set thereat, and back through wires 1, 9 and 13 to 55 the switch-arm m and so by wire 14 to the magnet M^2 and ground. The magnet M^2 then attracting its armature and so connecting the wire 15 to the wire 8, in order to maintain the primary selector switch in the 60 position it has assumed; and the wire 15

is also connected to the wire 16, and thence to wires 18 and 20, the former going to the switch-arm m' and thence by 19 to the indicator i and ground; and the wire 20 going to the contact s' of the solenoid relay 70 S , the twin contact s^2 being connected by wire 21 to the magnet M^3 , which controls the switch-arm m, m' and ground. These springs are normally separated, and the solenoid is so constructed that it will pull 75 up its core s very quickly, but it will permit it to fall very slowly. This end is attained by making the core slide like a plunger in the tube of the solenoid, the upper end of which is fitted with a valve 80 shown in dotted lines, and consisting of a small ball in a conical seat, opening through a central channel into the tube of the solenoid. When the core s is drawn up the air is expelled freely, raising the ball from 85 its seat, but when the solenoid is deenergized the ball falls into its seat and prevents the ingress of air in any quantity, the arrangement being similar to well-known dash-pots as used in door closers and 90 the like. The solenoid winding is connected on one side to ground and on the other through wire 17 to the back contact of relay M^2 . In order to prevent the solenoid 95 from being constantly energized when the apparatus is idle, I cause the magnet M' to control the continuity of the battery circuit 12-15, closing the same when it is energized only. The first flow of current through the wire 9 and magnet M^2 , produces no effect, because the springs s^1, s^2 100 are open, and the magnet i is merely energized to pull up its armature, without moving the wheel i^4 , which I should remark is stepped around on the back stroke or 105 retraction of the armature. The current now being reversed on the line, as previously pointed out, the magnet Q shows its target, and the subscriber taps the key K as many times as there are units in the 110 first digit to be sent. Assuming for example that the number he wants is 4468, he taps the key four times and then leaves it closed for a brief interval. Each tap breaks the circuit and permits the armature of relay M^2 115 to fall back. At the first falling back, this armature closes the circuit of the solenoid S as follows: B, 12, 15, 17, S and ground. The solenoid immediately pulls up and in so doing momentarily closes the springs s^1, s^2 , 120 but this produces no effect, since the wire 20 is on the front contact of the relay, which is opened when the solenoid pulls up. Each time the armature of the relay falls back and pulls up again, the battery circuit 125 through the wires 18 and 19 to the magnet i is broken, and this magnet therefore steps around its wheel i^4 four steps. During the four breaks produced in the line, the solenoid core s has remained up above the 130

springs, because as I have stated it retracts very slowly, and has not time to reach the springs during the brief intervals between the excursions of the relay armature. At the end of the first group of impulses, however, the relay M^2 remains energized, and the solenoid wire 17 is cut off for a long enough time to permit the core s to pass the springs and complete the following circuit momentarily: B, 12, 15, 16, 20, s^1 , s^2 , 21, 10 M^2 and ground. The magnet M^3 thereupon attracts and releases its armature, moving the switch-arms m , m' , one step, so that they rest upon the second contacts in their respective sets. The arm m does not produce any change in conditions, since the wire 13 is connected to both the first and second contacts; but the arm m' passes from the contact forming the terminal of wire 19 to the contact connected by wire 22 to the magnet i' , which is the second indicator magnet. The subscriber now makes a second group of breaks, whereupon the former operation is repeated, the magnet i' steps around the wheel i^3 to the fourth place, so that the two wheels together show the number 44, preferably through a little window in front of them. At the end of this group of breaks the subscriber leaves the key closed, the solenoid S lets go its core, the springs s^1 , s^2 are closed together for the second time, the magnet M^3 gets another momentary impulse of current, and the switch-arms m , m' are stepped around once more. The arm m now 25 passes on to a third contact forming a terminal of wire 23, which puts the battery wire 12 directly on to the magnet M^2 through wire 14, and maintains the same energized until the plug P is inserted. The arm m' passes on to a blank, so that the indicators 30 are entirely disconnected.

As soon as the operator perceives the number-wheels set, she knows that a line is connected to the corresponding jack, and that 35 the subscriber wishes to be connected with some other subscriber whose number commences with 44. She thereupon inserts the plug P into the jack J , and the plug P' into the trunk-jack J' (see Fig. 2) of the 44th group. The trunk-wires 24 and 25 from this jack lead to an automatic connector switch C , containing terminals of all the lines from 40 4400 to 4499.

Associated with the cord-circuits 26, 27, 55 28, 29, is a pair of solenoid relays S' , S^2 , constructed in the same manner as the solenoid S , as regards their cores, and the solenoid S' having also a similar pair of springs s^3 , s^4 . The solenoid S^2 , however, has five 60 springs, s^5 , s^6 , s^7 , s^8 , s^9 , of which the last four are normally held closed together, and the first named is left open, the insulating head on the lower end of the core being adjusted to maintain this condition when the apparatus is idle. When the solenoid is ener-

gized, however, springs s^5 , s^6 are closed together and the others are left individually open. Also associated with the cord-circuit, or with the answering end of it, 26—28, is a pair of relays S^3 , S^4 , which are bridged 70 across the core with the battery B between them. The armature of relay S^4 is connected by wire 30 to the battery wire 12, and when attracted connects the same through wire 31 to the armature of the relay 75 S^3 . The back contact of the latter is connected by wire 32 to a supervisory lamp L , and also by a wire 36, through wire 38 to the solenoid winding S' , through wire 39 to the spring s^5 of the other solenoid; the wire 36 80 is also connected through wire 37 to the spring s^8 of the same set. The spring s^9 is connected through wire 40 to the sleeve of the plug P , this plug being a three-way plug with tip, ring and sleeve contacts; tip and 85 ring contacts constituting the terminals for the talking circuit, wires 26 and 28. The spring s^7 is connected by wire 41 to the cord-conductor 29, and the spring s^6 by wire 42 to the cord-conductor 27. The cord-conductor 29 is also connected through wire 35 90 to the spring s^3 of solenoid S' , the other spring of this pair going by wire 34 to the wire 33, which terminates in the front contact of the relay S^3 , and is also connected to 95 the winding of the solenoid S^2 . The operation of these parts will be stated later. Before proceeding thereto I will describe the switch-circuits in Fig. 2, and the mechanism thereof in Figs. 3 and 4, the last first. 100

Referring to Figs. 3 and 4, I have therein illustrated a typical connector switch, comprising a frame c , constituting an up-standing flange around a flat plate c' , and carrying at its lower end the posts c^2 , upon which are mounted line and test contacts c^3 . Jounaled in the frame vertically, so that it may be moved up and down and also rotated therein, is a spindle c^4 carrying at its lower end the wipers c^5 , c^6 . The wiper c^6 can be 110 dispensed with, in the present case, as it will be observed I only use one pair in the diagram, but the lower wiper c^6 and its contacts are also provided, and if not employed for testing are found useful for attaching 115 line meters or other apparatus. The spindle is fitted with a pair of ratchets c^7 , c^8 , the former consisting of a series of circular teeth up and down the spindle, and the latter of a broad faced ratchet wheel having 120 long straight teeth extending parallel with the spindle. Coöperating with these ratchets is a common pivoted detent c^9 , having an arm c^{10} engaging the ratchet c^7 , a second arm c^{11} engaging the ratchet c^8 , and an upstanding bell-crank arm c^{12} carrying a pin c^{14} adapted to be engaged by the latch c^{15} on the armature c^{16} of the release magnet R^2 . When the armature is attracted the latch 125 c^{15} is thrown forward until it engages the 130

pin, then upon retracting it pulls over the bell-crank, leaving the arms c^{10} and c^{11} and permitting the spindle to be restored, the latch passing off the pin at the end of its movement, after the spindle has gone back to zero, which takes very little time. The spindle is stepped up by means of a pawl c^{17} , on an armature c^{18} , controlled by what I shall call the vertical magnet V' . It is stepped around by means of a ratchet c^{19} on the armature c^{20} of what I shall call the rotary magnet R' . This magnet also controls the pair of contacts c^{21} , which are connected in its own circuit, so as to make it a vibrator 15 or "buzzer." The armature c^{20} carries a projecting arm c^{22} , which passes down into position to engage the armature c^{23} , of what I shall call a private magnet T . The armature of this magnet also carries an escapement t , and controls contact springs lettered in the diagram. The escapement permits the movement one step at a time of what I shall call the side switch U , which is pivoted at u , and is restored to the position shown in 20 Fig. 3, by means of a bell-crank lever u' when the switch spindle is down, the upper or short arm of this lever engaging beneath the ratchet wheel c^8 and the end of the long arm engaging the upper end of the switch-lever. This side switch to which I have referred as U , has four arms shown in the diagram, Fig. 2, as u' , u^2 , u^3 , u^4 , all of which move together and are attached to the common block of insulation u^5 . The spindle is 25 restored and maintained in the position shown in Fig. 3 by a coil spring housed in the cap c^{24} , one end of the spring being attached to the spindle and the other end to the arm c^{25} , the end of which is perforated to receive the post c^{26} , upon which it travels up and down. A stop arm c^{27} is adjustably mounted on the spindle below the spring arm so as to determine the proper normal position for the spindle and the wipers. 30

Referring now to Fig. 2, V and R are what I shall call the vertical and rotary relays, respectively, bridged across the switch-trunk and grounded between their windings. The relay V controls the contacts v , v' , and relay R the contacts r , r' , a pair of intermediate ground contacts g coöperating with v' and r' . The parts in Fig. 2 being all lettered the same as in Fig. 3, further description thereof is unnecessary, and the nature of the circuits will sufficiently appear from the statement of operation, which I will now give.

The operation of calling and of indicating the first two digits of the number wanted, has been given. Proceeding, therefore, from that point, I will remark merely that when the plug P is inserted a clear through circuit from the line to the cord is obtained. The cut-off relay N in putting the wires 1—2 on to the wires 9—10, disconnects the line-

relay M , and the last step of the switch-arms m , m' disconnects the magnet M^2 from wire 9 and puts it on to wire 23, where it remains preferably until the plug P is finally pulled. As soon as this plug is inserted, a circuit is 70 completed as follows: battery B , 12, 30, 31, 32, 36, 37, s^8 , s^9 , 40, sleeve of plug P , jack thimble j^3 , 52, M^4 and ground. According to this preferable mode of operation, with the indicators and the magnet M^2 cut off 75 during the connection, it is necessary that the magnet M^4 should release the indicators upon the back stroke, that is only by pulling up and then releasing its armature. This sort of a release is illustrated in Fig. 80 3, where the magnet R^2 performs a similar function in a similar manner. Thus, when the plug is inserted, the release magnet is energized, but nothing further occurs. It is possible, however, for the two remaining 85 digits of the number to be taken on the indicators, or for that matter it obviously involves no departure from my invention to multiply the number of register wheels and the number of switch-contacts controlling them, so that all the digits will come in and be received in due order. The plug being in, the magnet M' is of course cut off, and current supply for the line and the cut-off relay N then passes from the main battery by 90 way of wire 12 through the relay S^3 to conductor 28, and so to wires 10, 4 and 2. The subscriber at the same time gains control of the relay S^3 , and he proceeds to send the last two digits of the number wanted, 95 which we have assumed to be 68. The armature of the relay S^3 being up as soon as the plug is inserted, the solenoid S^2 takes current, and pulling up its core opens the springs s^6 , s^7 , s^8 , s^9 , and closes s^5 , s^6 , thus 100 completing the following circuit for impulses to the trunk-wire 24: battery B , 12, 30, 31, 32, 36, 39, s^5 , s^6 , 42, 27, tip of plug P' . The first break of the group of six in the 105 next digit causes the armature of relay S^3 to fall back sending a pulse of current over this circuit into wire 24, through the branch 58 and magnet V to ground. At the same time the same pulse goes through wires 36 and 38 to the solenoid of S' and ground, 110 and this solenoid pulls up its core, momentarily closing the springs s^3 , s^4 , but producing no effect thereby since their circuit is open through wire 33 and at the front contact of relay S^3 . The magnet of relay V 115 becoming energized closes the following circuit: g , v , 61, t^2 , t' , 62, u' , 63, V' , 64, 65, 71, 72, battery B . Each time this occurs, that is for each break at the key K , the vertical magnet V' in Figs. 2 and 3 is energized to 120 step up the switch spindle c , one step. As there are six taps on the key, the wiper c^5 goes up to the 6th row. The pause which follows with the line closed, permits the core of solenoid S' to move all the way down, 125 130

closing the springs s^3 , s^4 together and sending a momentary pulse of current over the trunk 25 by the following path: B, 12, 30, 31, 33, 34, s^4 , s^3 , 35, 41, 29, P', J', 25, 59, R and ground. The relay R pulling up closes the following local circuit in the switch: g, r', 68, T, 70, 72, and battery. The relay T thereupon pulls up, and as will be seen by reference to Fig. 3, steps the side switch 10 arms around one step, thereby cutting off the magnet V', cutting on relay R', and through the arm u^4 connecting the wire 75 to the test wire 76. The next group of breaks at the key K also affects the vertical relay V in 15 the same manner and over the same circuit, the local circuit, however, being now as follows: g, v', 61, t^2 , t' , 62, u' , 51, R', 64, 65, 71, 72, B. The magnet R' thereupon steps the spindle around until the wiper c^6 rests on 20 the No. 8 contact pair in the 6th row. The subscriber then removes his hand from the key, and the circuit remaining closed the solenoid is operated as before, sending another single pulse from the trunk 25 and 25 through wire 59 to relay R and ground. This closes the same local circuit as before through the relay T, which pulls up on the impulse and at the instant of pulling up closes the following test circuit: B, 72, R², 30 (release magnet) 73, 74, t^4 , t^3 , 75, 76, c^5 , (tip side).

If the line wanted is busy it will have a ground on its tip side, either through a cord-circuit, relay S³, and a magnet M², or a connector switch magnet X. In any such case the release magnet R² will immediately work and send the switch back to zero before the talking circuit is completed by the last movement of the side switch. If the line is 40 not busy, however, this does not occur, and the magnet T completes its movement, releasing the side switch U for the third time, and completing the talking circuit to the called line by way of wires 56, 78, 80, 57, 77, 45 79. The third motion of the switch arm u' connects the wire 62 with the ringing relay wire 67, this relay R³ controlling the ringing key by which the generator D is connected to the wipers C⁵, the same being simultaneously disconnected from the trunk 50 wires 56 and 57. This ringing relay is operated by any number of short breaks which the subscriber chooses to send. If it is a party-line he may send 1, 2, 3 or 4 breaks, 55 each one of which will work the ringing relay by working the vertical relay V.

Battery current is supplied to the called line for talking purposes through the following path: B, 72, 11, X', 57, 77, 79, out on 60 the subscriber's line, back on the tip side, 80, 78, 56, X and ground. Condensers C', C² separate the trunk-circuits in order to prevent confusion during selection. A perfectly clean talking circuit is then provided 65 with only one pair of condensers, and

bridged battery feeding both ways. This is identically the same circuit which is now considered standard in manual switchboard installations. In this connection I should state that it is found advisable in practice to 70 make two back contacts for the armature of the relay S³, in order that the wire 42 and conductor 27 may not be constantly crossed with the solenoid wire 38 and the lamp wire 32. Both of these are grounded, which 75 would put a permanent ground on the tip side of the trunk, but if the wire 39 be made to terminate in a separate back contact, instead of being common with wire 36, this difficulty is avoided. When the subscribers 80 have finished conversing, they hang up their telephones; the relay S³ thereupon lets go its armature, and the solenoid S² loses current and for the first time since the actuation of the connection permits its core to fall all 85 the way down. The springs s^5 , s^6 are thereupon forced apart, and the other springs s^6 , s^7 , s^8 , s^9 are all forced together. Current thereupon flows over both sides of the cord and both sides of the trunk as follows: B, 90 12, 30, 31, 32, 36, 37, s^8 , s^6 , to conductor 27 and wire 24; also from s^8 to s^7 , conductor 29 and wire 25. From the wires 24 and 25 the circuit is on both sides through branches 58 and 59 and relays V and R to ground. These 95 relays pull up simultaneously, closing together the contacts v and r, and thereby closing the release magnet circuit as follows: B, 72, R², 73, 69, r, v, 60, ground. The release magnet thereupon restores the switch. At the same 100 time, the lamp L associated with the answering plug P glows, and the operator pulls the plugs P, P', whereupon the release magnet M² sets back the indicators to zero, and as the line-circuit is broken at the subscriber's station the magnet M² then loses current, opening the circuit 8, de-energizing the solenoid o^{11} , permitting the plug o^{13} to withdraw, and thereby releasing the primary 105 selector O, which resumes its travel over the line-contacts, and all is once more in condition to take another call.

Having thus described my invention what I claim and desire to secure by Letters Patent is:—

1. In a telephone exchange system, a plurality of line circuits, circuit terminals for the lines, an indicating device associated with the circuit terminals, means adapted to automatically connect the same to a calling 110 line in response to a call, means for controlling the same thereafter over the line, means for manually initiating a connection and extending the same in accordance with the indications, and electromagnetically controlled switching devices brought into connection with the manual means for automatically completing the connection thereafter, substantially as described.

2. In a telephone exchange system, a plu- 115 120 125 130

- rality of subscribers' lines and connective apparatus therefor composed of separable elements as follows: answering terminals, indicators associated with said terminals, 5 means adapted to automatically connect the same with the lines in response to calls thereover, means for thereafter controlling the same over the lines, manually operated devices for connecting the lines through one 10 or more links in accordance with said indications, and automatic switches electromagnetically controlled therethrough to complete the connections, substantially as described.
- 15 3. In a telephone exchange system a plurality of subscribers' lines, and connective apparatus therefor comprising the following instrumentalities: a number of answering terminals less than the number of lines, 20 automatic means for connecting a calling line with an idle one of said terminals, a number indicator associated with each terminal, means for extending the connection in accordance with the indications thereof, 25 and automatic means for completing the connection, substantially as described.
4. In a telephone exchange system a plurality of subscribers' lines and means for interconnecting the same comprising the following instrumentalities: a number of answering terminals less than the number of lines, automatic means for connecting a calling line with an idle terminal, an indicator associated with each terminal, and 30 adapted to be controlled through the calling line circuit, means for extending the connection in accordance with the indication when set, and automatic means for completing the connection, substantially as described.
5. In a telephone exchange system a plurality of lines and means for interconnecting the same comprising the following instrumentalities: a number of answering terminals less than the number of lines, an indication set including a numerical indicator 35 adapted to be controlled through the calling line circuit and means for automatically connecting a calling line to an idle answering terminal, and adapted to be controlled over the calling line, and connective apparatus adapted to be manually brought into association with the indication set, and thereafter to be automatically controlled 40 through the calling line, substantially as described.
6. In a telephone exchange system, a plurality of lines and means for interconnecting the same comprising the following instrumentalities: a number of answering terminals less than the number of lines, automatic switching means responsive to calls 45 over the lines for connecting a calling line with an idle terminal, a numerical indicator for each terminal, means for setting 50
- said indicators controlled through the calling lines, and automatic switching apparatus adapted to be manually brought into association with the answering terminal of a calling line and thereafter electromagnetically controlled to select, test and connect with the line wanted, substantially as described. 70
7. In an automatic telephone exchange system a plurality of lines and means for interconnecting the same comprising the following instrumentalities: a number of answering jacks less than the number of lines, an automatic primary selector switch adapted to be controlled by a line when 75 calling and to connect the same to an idle jack, an indicator associated with the jack and adapted to be brought under control of the line when so connected, a trunk line terminating in an automatic connector switch 80 containing calling terminals of a plurality of the line circuits, a plug and cord for connecting said trunk to the answering jack of a calling line, and means for controlling said switch from the subscriber's station, 85 substantially as described.
8. In a telephone exchange system a plurality of lines and means for interconnecting the same comprising the following instrumentalities: a number of answering 90 jacks less than the number of lines, a number indicator for each jack, means at each substation for operating said number indicator, and connective circuits having plugs and automatic switches, the latter less in 95 number than the number of lines, and containing calling terminals of the various line-circuits, the plugs and switches so arranged that the answering jack of a calling line may be connected to a switch corresponding 100 to the indication set, said switch thereafter being controlled over the calling line to 105 complete the connection, substantially as described.
9. In a telephone exchange system a plurality of lines and means for interconnecting the same comprising the following instrumentalities: a number of answering terminals less than the number of lines, an automatic primary selector switch adapted to be controlled by a calling line to connect the same with an idle answering terminal, a double digit number indicator associated 110 with each terminal and adapted to be operated over the line to indicate the hundreds 115 group in which the line wanted is found, a plug and cord-circuit and a plurality of automatic connector switches, each containing calling terminals for one hundred lines, said 120 plug, cord-circuit and switch being so arranged that a calling line may be connected to the particular connector switch which contains the terminal of the line wanted, substantially as described. 125
10. In a telephone exchange system a plu- 130

rality of lines and means for interconnecting the same comprising the following instrumentalities: a number of answering terminals less than the number of lines, a primary selector switch adapted to be controlled by a calling line to connect the same with an idle answering terminal, a double-digit number indicator associated with each terminal and adapted to be operated over the line to indicate the hundreds group in which the line wanted is found, a plug and cord-circuit and a plurality of automatic connector switches, each containing calling terminals for one hundred lines, said plug, cord-circuit and switch being so arranged that a calling line may be connected to the particular connector switch which contains the terminal of the line wanted, together with means whereby said switch may thereafter be controlled over the calling line to select the line wanted, substantially as described.

11. In a telephone exchange system a plurality of lines and means for interconnecting the same comprising the following instrumentalities: a plurality of answering jacks less than the number of lines, switching means automatically operated to connect a calling line with an idle answering jack, a hundreds indicator associated with each jack and controlled over a calling line, connective circuits comprising answering plugs and automatic connector switches, each containing the calling terminals of some particular one hundred lines, and a supervisory signal associated with each answering plug and controllable through the plug circuit, substantially as described.

12. In a telephone exchange system a plurality of subscribers' stations, a central office, and metallic circuits extending between the same, means at each subscriber's station for making and breaking the metallic circuit, together with connective means at the central office comprising the following instrumentalities: a plurality of answering jacks less in number than the number of lines, a primary selector switch connected to each jack and containing answering terminals of a number of lines, means whereby a line calling may cause said switch to pick out its terminals and connect the same to its answering jack when idle, an impulse-actuated indicator associated with each jack, and adapted to be connected to the line calling when its jack is so connected, automatic connector switches containing calling terminals of the various lines, manually operable means including a plug for connecting a connector switch to an answering jack, as designated by its indicator, and relays thereby brought under control of the calling line for actuating the switch to select the line wanted, substantially as described.

13. In a telephone exchange system a plu-

rality of subscribers' stations, a central office, and metallic circuits extending between the same, means at each subscriber's station for making and breaking the metallic circuit, together with connective means at the central office comprising the following instrumentalities: a plurality of answering jacks less in number than the number of lines, a primary selector switch connected to each jack and containing answering terminals of a number of lines, means whereby a line calling may cause said switch to pick out its terminals and connect the same to its answering jack when idle, an impulse-actuated indicator associated with each jack, and adapted to be connected to the line calling when its jack is so connected, automatic connector switches containing calling terminals of the various lines, manually operable means including a plug for connecting a connector switch to an answering jack, as designated by its indicator, and relays thereby brought under control of the calling line for actuating the switch to select the line wanted, together with means for removing the indicator from connection with the calling line when a plug is inserted in its jack, substantially as described.

14. In a telephone exchange system subscribers' metallic circuits, with means at the substations for making and breaking the same, a common source of current and a relay for each line, a number of answering terminals less than the number of lines, and an automatic primary selector switch associated with each terminal and adapted to be controlled by the line relay of a calling line to connect the same with its terminal when idle, an indicator associated with each terminal and brought under control of the calling line when so connected, automatic connector switches containing the calling terminals of the lines, means to connect a connector switch as designated by the indicator, to the calling line, and a supervisory signal associated with said connecting means, substantially as described.

15. In a telephone exchange system a plurality of subscribers' stations and a central office with metallic line-circuits interconnecting them, each line-circuit having a relay M, a cut-off relay N, multiple answering terminals o , o' , and calling terminals c , together with connective means comprising the following instrumentalities: a primary selector switch O, having traveling contacts and a circuit 9-10, together with means to connect the same with the line contacts o , o' , a jack J associated with the primary selector, an indicator I associated with the jack, electromagnets for the indicator, and a sluggish controlling relay S therefor, an automatic connector switch C, a trunk circuit 24-25 therefor, terminating in a jack J', a plug cord-circuit for connecting the jacks J, J', 130

- when required, and relays having different time constants associated with the cord-circuit and responding to current changes in a calling line to actuate and control the connector switch, substantially as described.
16. In a telephone exchange system, subscribers' stations and a central office with line circuits interconnecting them, normally disconnected answering terminals for the lines, means to connect the same in response to calls thereover, automatic connector switches containing calling terminals for the lines, means to connect any of said switches to any of the answering terminals, indicators associated with said answering terminals, terminals adapted to be controlled by the subscribers for designating the switches to be so connected, impulse sending means for actuating, and means for thereafter controlling the connected switches, substantially as described.
17. In a telephone exchange system, a plurality of line circuits and substations provided with sending devices, circuit terminals for the lines, indicating means associated
- with the terminals and adapted to be controlled by a calling line, means for manually initiating a connection in accordance with the indications, and means controlled by said sending devices for automatically completing the connections thereafter, substantially as described.
18. In a telephone exchange system, a plurality of subscribers' lines and substations provided with sending devices, connective apparatus therefor composed of links as follows: answering terminals, indicators associated with said terminals and adapted to be controlled by calling lines, manual connecting devices for initially connecting the lines in accordance with said indications, and automatic switches controlled by said sending devices to complete the connections, substantially as described.

In testimony whereof I affix my signature in presence of two witnesses.

EDWARD E. CLEMENT.
